(57) **CLAIM**

The ornamental design for a cutting tool, as shown and described.

DESCRIPTION

FIG. 1 is a top, front perspective view of a cutting tool showing a first embodiment of our new design.

FIG. 2 is a top plan view thereof.

FIG. 3 is a bottom plan view thereof.

FIG. 4 is a right side elevational view thereof.

FIG. 5 is a left side elevational view thereof.

FIG. 6 is a front elevational view thereof.

FIG. 7 is a rear elevational view thereof.

FIG. 8 is a top, front perspective view of a second embodiment of our new design.

FIG. 9 is a top plan view thereof.

FIG. 10 is a bottom plan view thereof.

FIG. 11 is a right side elevational view thereof.

FIG. 12 is a left side elevational view thereof.

FIG. 13 is a front elevational view thereof.

FIG. 14 is a rear elevational view thereof.

FIG. 15 is a top, perspective view of a third embodiment of our new design.

FIG. 16 is a top plan view thereof.

FIG. 17 is a bottom plan view thereof.

FIG. 18 is a right side elevational view thereof.

FIG. 19 is a left side elevational view thereof.

FIG. 20 is a front elevational view thereof; and,

FIG. 21 is a rear elevational view thereof.

The broken line showing of the rear portion of the cutting tool in FIGS. 1-5, 7-12, 14-19, and 21 is for illustrative purposes only and forms no part of the claimed design.
